UNITED STATES PATENT OFFICE

JOHN S. WALKER, OF PITTSBURGH, PENNSYLVANIA, ASSIGNOR TO KANT-GLARE MANUFACTURING COMPANY, INCORPORATED, OF PITTSBURGH, PENNSYLVANIA, A CORPORATION OF DELAWARE

ANTIGLARE DEVICE

Application filed February 29, 1932. Serial No. 595,943.

The invention relates to a reflector attachment for electric lamps, and more especially to an anti-glare device.

The primary object of the invention is the provision of a device of this character, wherein the construction thereof permits the application within a lamp house so as to confront an electric light bulb when placed therein so that the light from such bulb will be controlled in a manner to eliminate glare on the projecting of the light from the lamp house, the device being adaptable for headlamps, spotlamps or other lamps adapted for use on automobiles.

Another object of the invention is the provision of a device of this character wherein the application thereof to the lamp avoids any necessity of altering the make-up of the lamp or disturbing any of its assembled parts excepting the removal of its front glass, the device being applied to the front glass and is susceptible of convenient adjustment to locate the same properly with relation to the electric lamp for the use of the device as an anti-glare medium.

A further object of the invention is the provision of a device of this character wherein the light projected from the electric bulb will be intercepted or screened in a manner to disrupt the stream and thus subdue the said stream and being in effect a shaded light, thereby avoiding the blinding effect of the headlights upon pedestrians or other persons approaching along a roadway and at the same time assuring maximum driving vision by illumination ahead.

A still further object of the invention is the provision of a device of this character which is simple in construction, thoroughly reliable and efficient in its purposes, possessing but few parts, thus rendering it easy of assembly and also readily applicable for mounting within a lamp, free for adjustment, strong, durable, and inexpensive to manufacture.

With these and other objects in view, the invention consists in the features of construction, combination and arrangement of parts as will be hereinafter more fully described in detail, illustrated in the accompanying

drawing, which discloses the preferred embodiment of the invention, and pointed out in the claim hereunto appended.

In the accompanying drawing:—

Figure 1 is a front elevation of a headlamp 55 showing the device constructed in accordance with the invention applied thereto.

Figure 2 is a sectional view on the line 2—2 of Figure 1 looking in the direction of the arrows.

Figure 3 is an enlarged vertical sectional view of the device removed from the lamp.

Similar reference characters indicate corresponding parts throughout the several views in the drawing.

Referring to the drawing in detail and in order that the construction, mounting and operation of the device constituting the present invention may be accurately understood, there has been shown a motor vehicle headlamp A which may be of any conventional form. This headlamp preferably is equipped with the usual parabolic reflector B and is closed at its front end by a glass or panel C, the latter being removably fitted to the body 70 of the lamp A. Entering through the back of the headlamp A into the reflector is a lamp socket 5 carrying an electric bulb or lamp 6, the latter being formed with the usual stem or base removably engaged in 80 the forward end of the socket. As is well known, the ordinary lamp of this type projects a very strong stream of light providing a pronounced blinding effect upon persons whose vision is directed toward the head- 85 lamp.

The anti-glare device to be employed with the lamp A comprises a concavo-convex circular base 7 in the form of a vacuum cup having a central stud 8 at its convex side 90 and this stud has swiveled or countersunk therein the head 9 of a threaded bolt 10 for the mounting of a scoop-like reflector 11 and the coupling of the latter with the base.

The reflector 11 is preferably of the shape 95 as shown in Figures 1, 2 and 3 of the drawing and in the apex portion 12 thereof is an internally threaded socketed head 13 which is integral with the reflector 11 and this head receives the threaded bolt 10 for the coupling 100

of the reflector and vacuum cup 7 together. The reflector has an extended portion 14 and such reflector is adapted to confront the bulb 6 within the lamp A to intercept the stream of light on illumination of said bulb.

In the use of the device the vacuum cup 7 is mounted upon the inner face of the glass or panel C preferably centrally thereof and by the bolt 10 the reflector 11 can be turned 10 by the head 13 engaging said bolt so as to position the extended portion 14 at the required location within the lamp A to serve as an anti-glare medium to intercept the stream of light from the bulb 6 for eliminating the 15 blinding effect thereof upon pedestrians or persons approaching along a roadway and also assuring the reflection of the light in a manner to assure full vision by the illumination of the headlamp for a driver of an automobile.

What is claimed is:—

The combination with a headlamp casing having a reflector, a front glass, an electric light bulb arranged between said reflector 25 and glass, of an anti-glare device comprising a resilient vacuum cup body adapted to be engaged with the inner face of the front glass in alignment with the electric light bulb and having a central stud, a bolt embedded in 30 the stud centrally thereof and projected a distance therefrom, a scoop-like reflector having its apex engaged upon the bolt and contacting with the stud, and a nut forming a head for the bolt and threaded thereon to 35 fasten the scoop-like reflector thereto and seated against the stud of the cup, said scoop-like reflector at that portion below its apex being inclined rearwardly with respect to the casing and terminating close to the 40 reflector in said casing.

In testimony whereof I affix my signature.
JOHN S. WALKER.
